DOUBLE-THROW SWITCH MECHANISM

Lawrence Pierce, Edgewood, Pa., assignor to Westinghouse Electric Corporation, East Pittsburgh, Pa., a corporation of Pennsylvania

Application January 14, 1944, Serial No. 518,213

11 Claims. (Cl. 74—97)

My invention relates to mechanism for electric switches, and has for its general object to provide a mechanism for double-throw operation whose driven member performs a snap action when moving from any one to another of its three operating positions.

More specifically, the invention aims at devising a double-throw mechanism operating with snap action when moving in either direction into or out of its center position, which is distinguished by a construction of simple design, easy to manufacture and assemble and of minimum space requirements.

It is also an object, related to the foregoing, to design the entire double-throw guide action mechanism so that it may be placed within, or integrated with, an operating handle suitable for use in connection with different types of contact devices.

It is further among the objects of my invention to provide a double-throw switch mechanism in which a single spring is used for actuating the switch and for producing snap-action release when moving the mechanism in either direction between any two adjacent positions, thus doing away with the trigger or releasing springs usually required in double-throw snap-action switches.

The invention takes advantage of some features of a known type switch mechanism whose actuating handle member is coupled with a rotary switch member by means of a floating member which is connected with the actuating member by a spring and engages the driven switch member with a cam that also cooperates with a stationary pin. While this known mechanism is unsuitable for double-throw operation, the invention provides improvements that convert it into a double-throw switching device in accordance with the above-mentioned objects. This is achieved by providing the floating cam mechanism with stationary stop means which engage the cam portion of the floating member in two angularly spaced places so as to form three kinematic rest positions. According to a more specific feature of the invention, a rotatable driven member of the switch mechanism has two dog pins or the like coupling means for engaging the cam portion of the floating member, while a stationary part of the mechanism carries two stationary stop pins or the like abutments for providing the three just mentioned rest positions, these stationary abutments being spaced farther away from the shaft of the driven member than the dog pins so that the latter are

free to pass underneath the stationary stop pins during the rotation of the driven member. According to another feature, more specific than the one just mentioned, the floating member is provided with two inner shoulders for engaging the dog pins of the driven switch member, and has two outer shoulders adjacent to the inner shoulders for abutting against the stationary stops, respectively, in order to limit the angular travel of the floating member.

The above-mentioned and other objects and features of my invention will be understood from the following description of the two embodiments illustrated in Figs. 1 through 9 and 10, respectively, of the drawings:

Figure 1 represents a switch mechanism according to the invention by a sectional view extending in the radial plane denoted in Fig. 6 by the dash-and-dot line marked I—I, this figure 20 showing the switch in its neutral or mid position;

Fig. 2 shows the same switch, also in section, with the switch handle moved towards the right-hand position and the mechanism ready to be tripped;

Fig. 3 is an illustration similar to Figs. 1 and 2 and represents the switch mechanism tripped towards the right-hand position;

Fig. 4 is a similar illustration showing the 30 same mechanism in a position ready to trip from the right-hand position of Fig. 3 towards the mid position of Fig. 1;

Fig. 5 is a further illustration showing the mechanism in the left-hand position;

Fig. 6 is an axial cross-section through the 35 same switch mechanism with the individual elements thereof in a position corresponding to the mid position shown in Fig. 1;

Fig. 7 is a face view of the floating cam member of the mechanism according to Figs. 1 through 6;

Figs. 8 and 9 are axial and radial views respectively of the rotatable driven member of the mechanism; and

Fig. 10 is a section through a different modification of my invention showing the mechanism in mid position comparable to that illustrated in Fig. 1.

Referring to Figs. 1 through 9, numeral 10 50 denotes as a whole the driving member of the switch. Numeral 20 represents as a whole the rotary driven member to be actuated by the driving member 10 with snap action between a mid position and two outer positions. Numeral 30 55 represents the floating cam member which is in-

terposed between the driving member 10 and the driven member 20 in order to produce the just-mentioned snap motion. The numeral 41 (Fig. 6) refers to the stationary casing or frame structure of the switch which has parts for cooperation with the floating cam member and forms together with the cam member the three kinematic rest positions herebefore mentioned.

The driving member 10 forms a casing which encloses and protects the other individual elements of the mechanism. The driving member 10 has a substantially cylindrical portion 11 integral with a handle portion 12. A lug 13 is provided at the extreme end of the handle 12 and serves as an abutment for a coiled extension spring 19 which connects the driving member with the floating member 30. The portion 11 of the driving member has two projections 14 and 15 arranged at opposite sides of its inner periphery for cooperation with the floating member. A hub 16 forms an integral part with the other portions of the driving member 10 and has two lugs 17 and 18 serving to establish a temporary positive engagement between the driving member and driven member.

The driven member 20 of the mechanism includes a shaft 21 whose extension 22 forms a crank for actuating a contact device housed in, or mounted on, the stationary structure 40 (Fig. 6). A crank plate 23 is firmly mounted on shaft 21 and carries two dog pins 24 and 25 which are angularly spaced from each other at equal distances from the shaft 21. The crank plate 23 forms two shoulders 26 and 27 adjacent to the pins 24 and 25, respectively. When the driven member 20 is assembled with the driving member 10 as shown in Figs. 1 and 6, the shaft 21 of the driven member forms a pivot about which the driving member is rotatable. During such rotation, the dog pins 24 and 25 will establish a temporary locking or driving engagement with the floating cam member.

The floating cam member 30, as is best apparent from Fig. 7, has an opening 31 which in the assembled condition surrounds the shaft 21 with sufficient play to permit the floating member 30 to rotate about the shaft 21 as well as to perform a radial motion relative to the shaft. The lower portion of the opening 31 has a smaller width than the upper portion.

A larger opening of substantially arcuate shape is provided in the floating member 30 and extends symmetrical to opening 31. The edge of opening 32 forms a notch at 33 in order to provide a suitable rest or abutment for the end of the spring 19. The center portion of the arcuate opening 32 is bordered by a cam portion 34 whose lateral slopes terminate in two inner shoulders 35 and 36 which are bordered by outer shoulders 37 and 38, respectively. The outer peripheral edge of member 30 forms two shoulders 39 and 40 for cooperation with the lugs 14 and 15 of the driving member 10.

The stationary casing or structure 41 has a bearing in which the shaft 21 of the driven member 20 is journaled. Two stop pins 42 and 43 are firmly secured to the stationary structure and hence maintain a fixed position during the operation of the mechanism.

When the mechanism is assembled and placed in its mid position as represented by Figs. 1 and 6, the spring 19 pulls the floating member 30 towards the lug 13 so that the cam portion 34 of the floating member abuts against the stationary stop pins 42 and 43 and thereby secures

a rest position for the individual elements of the mechanism. In this position, the shoulders 35 and 36 of the floating member 30 engage the respective dog pins 24 and 25 of the driven member, thus determining a rest for the driven member. The shoulders 39 and 40 of the floating member 30 engage or lie close to the lugs 14 and 15 of the driving member 10. The lateral slopes of the cam portion 34 are preferably so shaped that their portions adjacent to the peak of the cam are substantially circular and have their center in the axes of dog pins 24 and 25, respectively.

Starting from this mid position of the mechanism (Fig. 1), the operation of the switch is as follows. When the handle portion 12 of the driving member is turned clockwise, the spring 19 has the tendency to entrain the floating member in the same direction. However, since the cam portion 34 of the floating member is wedged between the stationary stops 42 and 43, the member is at first not free to follow this tendency. It merely performs an angular motion about the dog pin 24. During this initial motion of the floating member, no force is exerted on the dog pin 24, and since further this pin rests against the cam portion 34 which at the point of engagement extends substantially transverse to the path of rotation of pin 24, no rotation is imparted by the floating member 30 to the driven member 20.

As the rotation of the driving member 10 proceeds, the force of spring 19 acting on member 30 will cause the floating member to move radially with respect to the shaft 21 until the peak of cam portion 34 passes underneath the stop pin 43. This intermediate stage of motion is represented in Fig. 2. In this position, the mechanism is ready to trip, that is, to release the driven member for rotary motion towards the right-hand position. The lug 17 of the hub portion 16 is so located that it engages or is about to engage the dog pin 24 in the just-mentioned tripping moment. Upon passing through this stage, the mechanism will permit the floating member 30 to follow the angular motion of the driving member about shaft 21 and to entrain the driven member 20 due to the engagement of stop 34 with dog pin 24. If for any reason the driven member should be retarded, for instance, by friction or sticking in the contact device to be actuated, the positive engagement between lug 17 and dog pin 24 will overcome such initial friction and hence secure the desired snap action.

The maximum deflection reached by the driven member 20 is shown in Fig. 3. According to this figure, the cam portion 34 of the floating member 30 has passed beyond the stop 43 and has permitted the spring 19 to move the member 30 radially towards the stop 13. The cam portion 34 has been forced to enter between pins 43 and 25 and, as a result, has rotated the driven member 23 and the shaft 21 with its crank 22 in the clockwise direction, thus placing the associated contact device of structure 40 into a corresponding contact position. When the floating member 30 reaches its end position, the stationary stop 42 is engaged by the outer shoulder 36 of the floating member and thus prevents further rotation of this member.

When turning the driving member 10 out of its mid position, the outermost end position reached by the handle portion 12 is slightly in excess of the angular motion to be effected by the driven member in order to ascertain a safe

snap action. This outermost position of the handle 12 is shown in Fig. 3. In this position, the shoulder 39 of the floating member may engage the lug 15 of the driving member. When now the handle 12 is released, the tension of the spring 19 will cause the driving member 10 to effect a slight angular return movement towards the mid position. In its final position of rest, the spring 19 lies again symmetrically with respect to the driving member.

Starting now from the right-hand end position just described, let us assume that the driving member 10 is turned back towards mid position. During the first portion of the handle motion, a rotation of the driven member 23 is prevented due to the fact that the dog pin 25 is engaged by the floating cam member while the latter is prevented from following the rotary motion of the driving member by the stationary stop 43. The frictional engagement of the contacts actuated by the driven member contributes also to retaining this member in its position of rest during this initial portion of the return motion of the driving member. The floating member 30, however, is forced to move so that cam 34 slides along pin 43 while the opposite inner edge of member 30 slides along pin 42. During the progress of this return motion, the mechanism will pass through the tripping position shown in Fig. 4. In this position, the radial motion of the cam member 34 towards the shaft 21 is at its maximum, and the peak of cam portion 34 is just underneath the stop pin 43. Upon passing through this phase of operation, the floating member 30 is free to rotate under snap action in the counter-clockwise direction until the cam portion 34 is again wedged between the stop pins 42 and 43. The mechanism then assumes the position of its individual elements shown in Fig. 1.

When turning the handle 12 of the driving member 10 from the mid position of Fig. 1 towards the left-hand position, i. e., in counter-clockwise direction, the floating member 30 is at first stopped by pin 42 and limited to a substantially rotational motion about the dog pin 24, simultaneously performing a substantially radial motion towards the shaft 21 until the peak of the cam 34 moves underneath the stop pin 42. Upon passage through this clearance or tripping point, the floating member 30 rotates counterclockwise under snap action and entrains the driven member 20 in a manner similar to the operation described in the foregoing. The final position reached by the mechanism is represented in Fig. 5. In this position, the further rotational motion of the floating member 30 about the shaft 21 is stopped by the engagement of shoulder 38 with the stationary stop pin 43.

When turning the handle 12 from the last-mentioned left-hand position back to the mid-point position, the snap-action operation is similar to the one described previously in conjunction with Fig. 4 except that now the stop pin 42 serves to retain the floating member 30 until the mechanism passes through the tripping stage.

It will be apparent from the foregoing that the two stationary stops 42 and 43 are sufficiently spaced from the shaft 21 to offer a free passage to the dog pins 24 and 25, as well as the other parts of the driven member 20. For a proper operation the shoulders formed at the opposite ends of the arcuate opening 32 in the floating member 30 must be so formed that while they engage the dog pins 24 or 25, these shoulders

do not interfere with the angular travel of the dog pins and the floating member relative to the stationary stops 42 and 43, with the exception of the right-hand and left-hand end positions in which the floating member 30 may directly engage the stationary stops 42 and 43 by the respective shoulders 37 and 38.

In order to permit a better understanding of the essential features of my invention as distinguished from those of mainly auxiliary nature, reference is had to the modification shown in Fig. 10. This modification is different in a number of individual features, but involves also the essential characteristics of my invention.

15 The driving member 10', according to Fig. 10, has a substantially cylindrical housing portion 11' which forms two rods 14' and 15' for cooperation with a stationary stop pin 54. This stop pin is firmly mounted on the stationary switch structure in addition to the stop pins 52 and 53 previously mentioned. When in operation, the angular motion of the driving member 10' about the shaft 21' is limited by the engagement of pin 54 with either the lug 14' or 15'.

20 25 The driven member has a substantially triangular crank plate 23' provided with two lugs 24' and 25', but having no shoulder portions comparable with shoulders 26' and 27' in Fig. 8 for cooperation with the stop pins 52 and 53. 30 These shoulders are unnecessary in the present embodiment because the motion of the driving member and the angular end position of the other elements of the mechanism are sufficiently determined by the additional stationary stop 54 in coaction with the lugs 14' and 15'.

35 The floating member 30' has shoulders 35' and 36' for engaging the dog pins 24' and 25', and forms also a cam portion 34' for cooperation with the stop pins 52 and 53.

40 The hub portion 16' of the driving member 10' differs from the one shown in the preceding embodiment by not containing lugs 17 and 18, although such lugs could also be provided if desired for greater reliability of operation. Similarly, the 45 floating member 30', according to Fig. 10, is simplified and has no outer shoulders comparable with shoulders 38 and 39 of the floating member 30 previously described. It will be understood, however, that such auxiliary means may also be 50 provided in the present modification.

When the driving member 10' is rotated from the illustrated mid position towards the left-hand or right-hand position, the spring 19' tends to entrain the floating member 30' in the same direction so that the latter causes the driven member 20' to follow in the same direction of rotation. However, the motion of the floating member 30' is at first controlled by the cam engagement between the cam portion 34' and one of the stop pins 52 or 53, so that the member 30' is limited to a radial motion towards the shaft 21' until the tripping point is reached. Then the floating member 30' is released for snap action and the driven member is entrained in a manner similar to the operation described in conjunction with the embodiment of Figs. 1 through 9.

55 In view of the above elucidated possibility of providing the modified mechanisms without departing from the objects and essential features of my invention, I wish this specification to be understood as illustrative and not in a limiting sense.

60 I claim as my invention:

65 1. A double-throw switch mechanism comprising in combination a rotatable driven member, a

coaxially rotatable driving member, a floating cam member for entraining said driven member, stationary stop means engaging said cam member so as to form three angularly spaced rest positions and two intermediate tripping positions, and a spring disposed between said driving member and said floating member for biasing it towards engagement with said driven member and said stop means.

2. A double-throw switch mechanism comprising in combination a rotatable driven member, a coaxially rotatable driving member, a floating member having two spaced shoulder portions for entraining said driven member for imparting thereto rotation in either direction and having a pointed cam portion intermediate said shoulder portions, two stationary stops angularly spaced from each other relative to the axis of rotation of said driven member for engaging said cam so as to form three angularly spaced rest positions and intermediate tripping positions for said floating member, and a spring disposed between said driving member and said floating member for biasing said floating member towards engagement with said driven member and said stops.

3. A double-throw switch mechanism comprising in combination a stationary structure, a shaft revolvable relative to said structure, a driven member mounted on said shaft and having two angularly spaced stop means, a driving member rotatable about said shaft, a floating member surrounding said shaft and being rotatable and radially displaceable relative thereto, said floating member having two angularly spaced shoulders for abutting against said stop means and a pointed cam between said shoulders, two angularly spaced stops mounted on said structure for engaging said cam so as to provide three angularly spaced rest positions and intermediate tripping positions for said floating member, and a spring disposed between said driving member and said floating member for biasing it towards engagement with said driven member and said latter stop means.

4. A double-throw switch mechanism comprising in combination a rotatable driven member having two angularly spaced dog pins at equal distances from the axis of rotation, two stationary stops spaced angularly from each other and arranged at equal distances from said axis and farther away than said dog pins to permit the latter a free passage during rotation of said driven member, a floating member having two spaced shoulders for engaging said dog pins respectively and forming a pointed cam between said shoulders for engaging said stops so as to have three angularly spaced rest positions and intermediate tripping positions, and a spring disposed between said driving member and said floating member for biasing it towards engagement with said dog pins and stops.

5. A double-throw switch mechanism comprising in combination a rotatable driven member having two angularly spaced dog pins at equal distances from the axis of rotation, two stationary stops spaced angularly from each other and arranged at equal distances from said axis and farther away than said dog pins to permit the latter a free passage during rotation of said driven member, a floating member having two spaced inner shoulders for engaging said dog pins respectively, two outer shoulders adjacent to said respective inner shoulders for abutting against said stops respectively in order to limit the travel of said floating member, and a pointed cam

formed between said inner shoulders for slidably engaging said stops so as to provide three angularly spaced rest positions and intermediate tripping positions for said floating member, and a spring disposed between said driving member and said floating member for biasing said floating member towards engagement with said dog pins and stops.

6. A double-throw switch mechanism comprising in combination a rotatable driven member having a shaft and two symmetrically arranged projections spaced equally from said shaft, two stationary stops angularly spaced from each other at equal radial distances from said shaft larger than those of said projections to permit the latter a free passage during rotation of said driven member, a floating member of flat and symmetrical shape having an opening elongated in the direction of the symmetry axis and surrounding said shaft so as to permit said floating member rotational and radial motion relative to said shaft and having also a generally arcuate edge forming a pointed cam with a cam point on said symmetry axis for engagement by said stops so as to provide for said floating member three angularly spaced rest positions with intermediate tripping positions, said edge forming two symmetrically arranged shoulders adjacent to said cam for engaging said projections respectively, and a spring disposed between said driving member and said floating member for biasing it towards engagement with said projections and stops.

7. A double-throw switch mechanism comprising in combination a rotatable driven member, a coaxially rotatable driving member, a floating member having a centrally located cam and forming two abutments at both sides of said cam respectively for engaging said driven member, stationary stop means arranged in a fixed position relative to the axis of rotation of said driving and driven members for engagement by said cam so as to form three angularly spaced rest positions and intermediate tripping positions for said floating member, said floating member having also shoulders for abutting in its two end positions against said stop means, and a spring disposed between said driving member and said floating member for biasing it towards engagement with said driven member and said stop means.

8. A double-throw switch mechanism comprising in combination a rotatable driven member having a shaft and two symmetrically arranged projections spaced equally from said shaft, two stationary stops angularly spaced from each other at equal radial distances from said shaft larger than those of said projections to permit the latter a free passage during rotation of said driven member, a floating member of flat and symmetrical shape having an opening elongated in the direction of the symmetry axis and surrounding said shaft so as to permit said floating member rotational and radial motion relative to said shaft and having also a generally arcuate edge forming a pointed cam with a cam point on said symmetry axis for engagement with said stops so as to provide for said floating member three angularly spaced rest positions with intermediate tripping positions, said edge forming two symmetrically arranged inner shoulders adjacent to said cam for engaging said projections respectively and two symmetrical outer shoulders for abutting in the two end positions against said stops when the latter are out of engagement with said cam, and a spring disposed between said driving member

and said floating member for biasing it towards engagement with said projections and stops.

9. A double-throw switch mechanism comprising in combination a rotatable driven member, a coaxially rotatable driving member, a floating member having two spaced shoulder portions for entraining said driven member for imparting thereto rotation in either direction and having a pointed cam portion intermediate said shoulder portions, two stationary stops angularly spaced from each other relative to the axis of rotation of said driven member for engaging said cam so as to form three angularly spaced rest positions and intermediate tripping positions for said floating member, said driven member and said floating member each forming two angularly spaced abutments for engaging a different one of said stops in either end position of rotation of said driven member and floating member, respectively.

10. A double-throw switch mechanism comprising in combination a shaft, a crank member rotatable about the axis of said shaft and having two projections spaced equally from said shaft and two abutments adjacent to said projections respectively and spaced from said shaft a larger distance than said projections, two angularly spaced stationary stops arranged in a fixed relation to said shaft axis for engagement by said abutments respectively when said crank member is in either end position of its rotation, a floating member having an opening elongated in the direction of the symmetry axis and surrounding said shaft so as to permit said floating member

5 rotational and radial motion relative to said shaft and having also a generally arcuate edge forming a pointed cam for engagement by said stops so as to provide for said floating member three angularly spaced rest positions with intermediate tripping positions, said edge forming two spaced shoulders for engaging said projections respectively and having two abutments for engaging said stops respectively in either end position of rotation of said floating member.

10 11. A double-throw switch mechanism comprising in combination a driving member and a driven member both movable between two end positions and an intermediate position, stationary stop 15 means disposed in a fixed relation to the path of motion of said member so as to form abutments for limiting the motion of said driven member in said two end positions respectively, a cam member 20 engaging said driven member and movable relative to said stop means and said driving and driven members along said path and towards and away from said stop means, said cam member being arranged for engaging said stop means so as to provide a rest in said intermediate position 25 and tripping points between said three positions, and a spring disposed between said driving member and said cam member for elastically entraining the latter while biasing it towards engagement with said stop means and driven member 30 in order to produce snap action for each change of position of said driven member.

LAWRENCE PIERCE.
